Primary Examiner — Mark A Goodwin(74) *Attorney, Agent, or Firm* — Peter Zacharias; Patrick Sheldrake(57) **CLAIM**

The ornamental design for an agricultural baler, as shown and described.

DESCRIPTION

FIG. 1 is a front perspective view of an agricultural baler of the present design.

FIG. 2 is a rear perspective view of the agricultural baler of FIG. 1.

FIG. 3 is a front view of the agricultural baler of FIG. 1.

FIG. 4 is a rear view of the agricultural baler of FIG. 1.

FIG. 5 is a left side view of the agricultural baler of FIG. 1.

FIG. 6 is a right side view of the agricultural baler of FIG. 1; and,

FIG. 7 is a top view of the agricultural baler of FIG. 1. The dashed lines shown in the figures form no part of the claimed design.

1 Claim, 7 Drawing Sheets(56)
